3 Claims. (Cl. 101—11)

This invention relates to branding and more particularly to an automatic apparatus for branding.

Frequently it is desirable for manufacturers to identify their products so that the consumer may readily recognize it. In many industries where large numbers of articles are identified with the manufacturer's imprint, such as a trademark or trade name, the imprint is placed on the article by stamping or branding. In the wood industry for instance, it has been found desirable to use a branding tool to imprint the manufacturer's mark on wooden poles after the poles have been debarked. The branding tool is conventionally an electric branding iron, a gas heated brander or a hammered die. Heretofore such imprinting has been hand operated so that great amounts of handling of poles and branding tools were involved. Furthermore, due to the inefficiencies of hand operation the possibility exists that not every pole was branded before shipment. It is universally recognized consequently, that an automatic imprinting means is needed to avoid these disadvantages.

An object of the present invention, therefore, is to provide a remotely operated apparatus which will automatically place an imprint on an article.

A further object is to provide an imprinting apparatus which is actuated by the delivery of an article thereto so that the imprinting of the article is assured.

The invention contemplates a novel apparatus for placing a manufacturer's mark on an article by way of an imprinting tool which is automatically lowered on to the article to be marked as the article is received and after the imprinting of the mark on the article, the imprinting tool is automatically lifted and the article discharged.

The above and further objects and novel features of the invention will appear more fully from the following detailed description when the same is read in connection with the accompanying drawings. It is to be expressly understood, however, that the drawings are not intended as a definition of the invention but are for the purpose of illustration only.

Fig. 1 is a schematic drawing showing the mechanical components, the pneumatically operated components and the electrically operated components of the invention.

Fig. 2 is a partial elevation of the main components shown in Fig. 1.

Fig. 3 is a partial cross section of components of Fig. 2.

Fig. 3a is a detail of actuating means and other components shown in Fig. 3.

Referring to Fig. 1, the imprinting tool A and the article receiving and holding means B of this invention cooperate with actuators C and control means D so that the branding operation is substantially automatic.

Referring more particularly to Fig. 1 the imprinting tool A, sometimes called the brander A, comprises an electrically heated element 11 held by holder 12. A parallelogram type linkage E connects imprinting tool A

2

to an actuator C and control means D so as to brand an imprint on a pole at an appropriate interval. To this end the holder 12 is attached to a guide arm 13 which is swivelly mounted on upright 19 by rotatable pin 17, the upright being supported by any suitable means well known in the art. Another guide arm 20 is also swivelly mounted on upright 19 by a pin 21 and a connecting arm 22 is connected to the two guide arms 13 and 20 by pins 23 and 24, respectively, so that any upward or downward motion imparted to one guide arm is imparted to the other and to the imprinting tool A in such a manner that the tool A is maintained in an upright vertical position at all times.

Air actuating cylinder 25 provides the upward and downward actuation for tool A and to this end the cylinder 25 is connected to a base 26 by a suitable rotatable linkage 27. The piston 28 of cylinder 25 is connected to guide arm 13 by a suitable rotatable pin 29 inserted in the piston arm 30. Together with a lubricator 32, a gage 33 and regulator valve 34 means are provided for the proper actuation of cylinder 25 from an air source 31 through suitable air lines to be described hereinafter, choke valves 35 and 36 and a two-way valve 37 which is part of a solenoid valve 38.

A relay coil 38₁ of the solenoid valve 38 controls the direction of air flow from the two-way valve 37 to selectively move the piston 28 of cylinder 25 up or down. By conventional means (not shown) the valve is returned when coil 38₁ is de-energized to the position which it had subsequent to energization of the coil 38₁ in the conventional manner of a two-way solenoid valve as is well-known in the art. When the apparatus is ready to receive the pole for branding the relay coil 38₁ is de-energized so that the valve 37 causes air pressure to flow to the bottom of cylinder 25 in which case piston 28 is held at the top of its stroke by air pressure from air source 31 in air lines 39, 40, choke 36 and air line 41. Consequently the piston arm 30 holds the guide arm 13 against the pivotally mounted actuating arm 32 of a double contact limit switch 43 so that armature 44 of the switch is engaged with its contact point 45.

When a pole is to be branded relay coil 38₁ is energized to cause the piston 28 and the imprinting tool A to move downward for branding. This operation takes place when a debarked pole P (Fig. 3) carried by moveable carrying arm 61 connected to moving belt 62, drops off a moving ramp 63 into yokes 64 and 65 which have fixed members 67 and 69 and moveable gates 70 and 71. When the pole P drops into these yokes the pole P is firmly cradled or yoked. As the pole drops into the yokes 64 and 65 the weight of the pole moves pivotally mounted impeller arm 74 (Fig. 3a) which is advantageously connected to the yoke 64 by pin 73, against an actuating arm 75 of a limit switch 76 so that normally open armature 77 engages contact 78. It will be noted that while the impeller arm 74 and the limit switch 76 shown herein are attached to yoke 64 they may, if desired, be attached to yoke 65 without in any way affecting their function. When this contact of armature 77 and contact 78 of limit switch 76 is made, a circuit is completed from a suitable energy source 79 to energize a conventional time delay relay 80 through lead 81, normally closed contact 83 and armature 85, lead 86, junction 87, lead 88, junction 89, lead 90, armature 77, contact 78, lead 91, relay 80, lead 92, contact 45, armature 44 to ground. The armatures 93 and 137 of relay 80 are moved upwardly upon energization of the relay. Thus the armature 93 engages a contact 95 completing a circuit to energize relay 38₁ from energy source 79 through junction 87, lead 98, relay 38₁, lead 99, contact 95, armature 93 to ground. The energization of relay 38₁ then causes valve member 46 of valve 37

to move so that air lines 40 and 41 are vented through vent 47 and air lines 48 and 49 are pressurized through choke 35 to the top of cylinder 25, thus causing the piston 28 to move downward. It is to be noted that when the piston 28 moves downward the guide arms 13 and 20 are pulled downward causing the arm 13 to be removed from the actuating arm 42 of switch 43 so that a spring 55 disengages armature 44 of switch 43 from contact 45 and engages armature 44 with contact 57.

In order to hold the tool A against the pole P for a suitable branding interval a holding device 95, well known in the art, is attached to relay 80 to hold the armatures of relay 80 upward for a suitable interval of time and this time interval is initiated by the de-energization of relay 80, i.e., by the disengagement of armature 44 and contact 45. Such a device is a Square D Company adjustable pneumatic timing relay, Class 9050, Number RW12D and such holding devices are preferably of the adjustable type so that the holding interval may be set anywhere from a few seconds to several minutes as required or desired. After energization of relay 38₁ for as long as its armature 93 and contact 95 are held engaged by the holding means 95, air pressure will be supplied to the top of cylinder 25 so that the tool A remains in contact with the pole P for the proper interval for branding.

To return the brander to its original position for receiving the next pole P₁ for branding after the predetermined interval of time elapses then the holding device 95 drops the armatures of relay 80 and the resulting disengagement of armature 93 and contact 95 de-energizes relay 38₁ causing valve member 46 to be rotated so that air lines 48 and 49 are vented and air lines 40 and 41 are pressurized. When air lines 40 and 41 are pressurized the piston 28 rises and the tool A is returned to its original position (shown in Fig. 1) at the top of its stroke for the beginning of a new branding cycle.

The branding means has been described with its actuating means and control means. As mentioned previously the branding means and the pole holding means cooperate to hold the pole while being branded and this operation is such that after the pole has been branded the holding means, in a manner to be described hereinafter, removes the branded pole from the brander so that another pole may be received for branding.

The holding means comprises yokes 64 and 65 which are spaced apart from each other and mounted on a base 97 which in turn is suitably mounted as shown in Figs. 2 and 3. Each yoke comprises a fixed member and a moveable gate member, as described above, and the latter are moveable in such a way that, when they are in an upward position, they form a V groove with the fixed members for receiving and holding a pole for branding and when they are in their downward position they cause the branded pole to fall to a canted receiving incline 99. The fixed members 67 and 69 are supported by bases 97, 101 and 19 in a suitable manner and the moveable gate members 70 and 71 are fixed to a rod 103 which is moveable in the fixed members 67 and 69 and secured thereto by nuts 105 and 107 so that the gates 70 and 71 and the rod 103 are moveable together.

The moveable gates are reciprocated upwardly and downwardly by an air cylinder 109 which is fixed to base 97 by a strap 111 and suitable nuts and bolts. Advantageously the cylinder 109 is attached to the gate 70 by a moveable linkage pin 113. Actuation of this air cylinder is provided by air source 31 through suitable air lines to be described hereinafter, two choke valves 115 and 117 and a two-way valve 119 which is part of a solenoid valve 121. Lubricator 32, gage 33, and regulator valve 34 are also connected to these air lines.

A relay 121₁ which is also part of solenoid valve 121 controls the direction of air flow from the two-way valve 119 to selectively move the gates up and down at the

proper time and this relay has a means (not shown) to return it to its de-energized position subsequently to energization in the manner of a two-way solenoid valve well known in the art. When the apparatus is ready to receive a pole for branding this relay 121₁ is de-energized so that air lines 125 and 126 are pressurized. Piston 127 in cylinder 109 is held in its position at the bottom of the cylinder 109 when lines 125 and 126 are pressurized. Rod 129 of piston 127 is connected to the gate 70 by pin 113 and at this time holds the gates 70 and 71 from moving when a pole drops into yokes 64 and 65.

After the pole has been branded relay 121₁ is energized to open the gates for the ejection of the pole by a sequence whereby a pole dropping into the yokes 64 and 65 causes armature 77 and contact 78 to engage as described above. This completes the circuit, also described above, to energize relay 80 so that relay 38₁ is energized, thus causing the tool A to move downward to brand the pole and so that armature 44 and contact 57 engage for a suitable time interval and whereby after the holding apparatus 95 drops the armatures of relay 80, thus closing the armature 137 with a contact 139, the relay 121₁ is energized from junction 89 through lead 140, armature 137, contact 139, lead 141, relay 121₁, lead 142, contact 57, armature 44 to ground. Thus after the pole P is branded relay 121₁ is energized so that valve member 123 is moved, causing air pressure in lines 125 and 126 to be vented through choke 115 and a vent 131 which causes air pressure to flow through air lines 133, choke 117 and air line 135 to the bottom of cylinder 109 so that the piston 127 is raised. This causes the gates 70 and 71 to open and the pole P which was held for branding is ejected to a canted receiving incline 99.

So that the gates may be returned to their closed position for receiving and holding another pole P₁, the ejection of the pole causes spring 144 to disengage armature 77 from contact 78. Simultaneous with this, armature 93 disengages from contact 95 causing relay 38₁ to be de-energized thus actuating the valve member 46 to cause the tool A to return to its upper position. After the tool A returns to its top position it disengages armature 44 from contact 57. When armature 44 and contact 57 are disengaged, relay 121₁ is de-energized thus moving valve member 128 to vent lines 135 and 133 through vent 131 and pressurizing lines 125 and 126; thus piston 127 is moved downward to cause the gates 70 and 71 to be closed for receiving another pole P₁ to be branded.

In operation when armature 95 is moved to engage contact 83 of an "off-on" switch 143 and relays 38₁, 80 and 121₁ are de-energized, the tool A will be at the top of its stroke and the gates 70 and 71 will be closed. This is the condition illustrated in Fig. 1. The yokes and gates are then in a position to receive a pole P for branding. The moving belt 62 and carrying arm 61 (Fig. 2) along the incline 63 and pick up a pole P which is then de-barked. The pole then drops into the yokes constituted of fixed members 67, 69 and gates 70, 71. The weight of the dropping pole causes armature 77 to engage contact 78. This engagement energizes relay 80 so that its armatures are moved upwardly. The resulting engagement of armature 93 and contact 95 energizes relay 38₁. When relay 38₁ is energized the tool A moves downward causing the pole to be branded as shown in Figs. 2 and 3. The downward movement of the tool A also causes armature 44 and contact 45 to disengage and armature 44 and contact 57 to engage. The disengagement of armature 44 and contact 45 initiates the running of the time delay interval in holding mechanism 95. After this predetermined time delay (long enough for the tool A to properly brand the pole P) the holding device 95, attached to the relay 80, pulls the armatures of relay 80 downwardly thus completing the circuit which energizes relay 121₁ and opens the circuit to relay 38₁. The de-energization of relay 38₁ causes valve member 46 to

move so that the tool A is raised while choke 35 controls the venting of lines 48 and 49 to raise the brander at a controlled rate. The energization of relay 121 causes the valve member 123 to move so that gates 70 and 71 are opened, thus ejecting the pole to the canted receiving incline 99. Choke 115 controls the venting of lines 125 and 126 to keep the gates from opening until after the brander has a chance to move upward slightly out of the way of the pole P when it drops to the incline 99. As the brander returns to the top of its stroke, arm 13 disengages armature 44 from contact 57 so that relay 80 is de-energized and this moves valve member 123 so that gates 70 and 71 are closed for receiving the next pole P₁, and armature 44 engages contact 45 and spring 144 causes armature 77 and contact 78 to disengage for the beginning of another branding cycle which is initiated by a pole dropping off the end of the moving ramp 63 to the yokes 64 and 65.

The brander element as illustrated herein is heated at all times during its operation. It should be noted that the choke valves 35, 36, 115 and 117 are provided with adjustments for proper sequencing of the operation of the apparatus.

When the various adjustments are made the apparatus of this novel invention operates automatically to brand every pole received thereby, the brander being actuated by an actuating means at the proper interval and the pole holding means cooperating therewith by means of a properly controlled actuating means, to hold the pole for branding, to eject the branded pole and to return the holding means and the branding means to their original positions for receiving another pole P₁ for branding at the proper interval.

Although the foregoing has illustrated and described the invention in detail, it is to be expressly understood that the invention is not limited thereto. Various changes can be made in the design and arrangement of the parts without departing from the spirit and the scope of the invention as will now be understood by those skilled in the art.

What is claimed is:

1. An apparatus for marking a pole having a substantially round cross section comprising electrically heated imprinting means, first pneumatically operated raising and lowering means for said imprinting means, first electrically operated actuating means to selectively actuate said first pneumatic means, selectively engageable pole holding means having a moveable member adapted alternately to close so as to form a substantially V-shaped groove which cradles said pole adjacent its ends and which opens so as to release said pole, a second pneumatically operated raising and lowering means for said moveable member, and a second electrically operated actuating means to selectively actuate said second pneumatic means so that said holding means and said actuating means cooperate to imprint said pole and

to eject said pole sideways after said article is imprinted.

2. An apparatus for marking a pole having a substantially circular cross section comprising an electrically heated branding element, a series of levers attached to said element for maintaining said element in an upright vertical position, a first air cylinder attached to said levers for raising and lowering said element to brand said poles, a pole holding means having a moveable gate member for cradling said pole adjacent its ends, a second air cylinder attached to said gate, and control means having a time delay mechanism cooperating with said first and second air cylinders for branding a pole in said holder and for ejecting said pole sideways after it is branded.
- 15 3. An apparatus adapted to mark a substantially cylindrical pole comprising a fixed support, a moveable die for marking said pole, a pair of spaced levers, means pivotably connecting one end of each lever to said die, means pivotably connecting the other end of each of said levers to said fixed support, whereby said levers are maintained parallel to each other whereby the movement of said die is maintained in a straight line, first pneumatic means for reciprocating said die, said first pneumatic means having inlet and outlet means, an air source, 20 a first solenoid actuated two-way valve connecting said inlet and outlet means, two spaced yokes connected to said fixed support so as to cooperate with said die and constituting a V-shaped cradle for said pole to hold said pole in the line of movement of said die, said yokes having one fixed member and one moveable gate member, second air actuating means for selectively moving said gate member to open and close said yokes, said second air actuating means having an inlet and outlet means, a second solenoid actuated two-way valve connecting the latter inlet and outlet means to said air source; and coordinating control means for said first and second solenoid actuated two-way valves including an electropneumatic timer for automatically actuating said first pneumatic means to move said die against a pole 25 30 35 40 45 50 cradled in said yokes to hold said die against said pole cradled in said yokes for a predetermined time and to remove said die from said pole cradled in said yokes after the elapse of a predetermined time, said coordinating control means also for actuating said second pneumatic means to hold said gate members so as to close said yokes when said die is being marked by said die and for moving said gate members so as to open said yokes to remove a pole sideways from said yokes after marking and for moving said gate members so as to close said yokes after said marked pole is removed so as to ready said yokes for receiving another pole to be marked.
